UNITED STATES PATENT OFFICE.

EUGENE E. LANDAHL, OF OAK PARK, ILLINOIS.

CONVEYING AND SCREENING APPARATUS.

Application filed November 22, 1920. Serial No. 425,881.

To all whom it may concern:

Be it known that I, EUGENE E. LANDAHL, a citizen of the United States, residing at 711 North Ridgeland Ave., Oak Park, Illinois, have invented certain new and useful Improvements in Conveying and Screening Apparatus; and I do hereby declare the following to be a full, clear, and exact description of the invention, such as will enable others skilled in the art to which it appertains to make and use the same.

This invention relates to conveying and screening apparatus; and while the principles of the invention are applicable broadly to apparatus for conveying and screening articles and materials generally, the invention relates more particularly to apparatus for conveying and screening coal.

Coal as it comes from the mine is in lumps of various sizes mixed with fine coal, dust and dirt. The slack or fines which is present in considerable quantity in run of the mine coal is practically worthless except for special purposes and it is therefore necessary to separate this slack from the lump coal. It is also necessary to separate from the coal fragments of slate and similar materials which have no combustible value and which are mixed with the good coal as it comes from the mine. While the slack or fines is ordinarily of little or no value, it is of the utmost importance that after being separated from the good coal it be conveyed to some convenient point for collection or disposal instead of allowing it to accumulate wherever it may fall after being separated. It is desirable that the number of conveyors, chutes, etc., used to carry the coal from the mine to the car be as small as possible to avoid subjecting the coal to consequent breakage and formation of additional quantities of slack or fines due to this handling.

It is a principal object of the present invention to provide apparatus which will not only completely and thoroughly separate fines from lumps, but which will also convey the separated fines and lumps simultaneously in the same direction to separate points of discharge while at the same time preventing the formation of additional quantities of fines or slack by avoiding rough and unnecessary handling.

Broadly speaking, the improved apparatus is characterized by a conveying and screening surface made up of an endless series of connected screen sections adapted

to convey the large lumps and allow the fines to drop through the screen sections on to a conveyor-trough below and to be simultaneously conveyed in the same direction with the lumps, the lumps and fines being carried to separate points of discharge. As a means for ensuring complete separation of the lumps from the fines the conveyor-screen is most desirably adapted to carry the coal up an incline and then down another incline in order to allow a certain amount of sliding and gentle agitation of the coal being carried and thus to secure the thorough screening desired. The separating effect thus obtained is especially effective by reason of the novel construction and arrangement of the elements comprising the endless conveyor-screen, as will hereinafter appear. A subsequent substantially horizontal run of the conveying and screening surface provides a picking table to allow slate and similar incombustible material to be picked out.

A practical embodiment of the principles of the invention will now be described in detail and further advantages of the improved construction will be pointed out. The particular construction here illustrated serves merely as an explanatory example of apparatus within the scope of the broad invention and it is to be understood that various changes in mechanical details and arrangement may be made without departing from the broad invention. The apparatus illustrated in the accompanying drawings is adapted more particularly for use in conveying and screening coal.

In the drawings,

Fig. 1 is a diagrammatic side elevation of one practical form of apparatus embodying my invention;

Fig. 2 is an end view of the same looking from the right in Fig. 1;

Fig. 3 is a fragmentary top plan view of the conveyor-screen on an enlarged scale;

Fig. 4 is a fragmentary longitudinal sectional view on line 4-4 of Fig. 3;

Fig. 5 is a transverse sectional view taken on line 5-5 of Fig. 4.

Referring to the drawings, 10 indicates generally an endless conveyor having a conveying and screening surface 11 attached to and carried by two strands 12 and 13 of endless roller chain passed around pairs of end sprocket wheels 14 and 15. These pairs of sprocket wheels are mounted on shafts 16 and 17 journaled in bearings 18 and 19 re-

spectively, supported by a suitable framework (not shown). At least one set of bearings is adjustable so that the tension of the conveyor-screen may be adjusted. Suitable means (not shown) are employed for driving at least one pair of the sprocket wheels to advance the screening and conveying surface. The upper run of the conveyor-screen is passed over and supported by a pair of sprocket wheels 20 mounted on shaft 21, said shaft being journaled in adjustable bearings 22 supported by a suitable framework (not shown). The sprocket wheels 20 are mounted intermediate and at a higher level than the end pairs 14 and 15, which latter are substantially on the same level, a hump or knuckle being thus formed in the upper run of the conveyor-screen in order to cause a thorough and complete screening of the coal by the conveying and screening surface. In the particular apparatus illustrated, the intermediate sprocket wheels 20 are so mounted between the end pairs 14 and 15 that the upper run of the conveying and screening surface forms a substantially horizontal run 23, an upwardly-inclined run 24, a downwardly-inclined run 25 and a second substantially horizontal run 26. The run of the mine coal is fed from the coal tipple at the mine, for example, on to the first substantially horizontal run 23 of the screening and conveying surface by chute 27. In landing on the conveying and screening surface, the coal will partly screen itself, some of the fines passing through the screen surface; while the lumps, together with some of the unscreened fines, are carried forward by the advancing conveyor-screen. As the conveyor-screen advances up the incline 24, a certain amount of sliding back occurs and a resultant gentle agitation of the coal on the conveyor will take place, thus promoting a further screening effect which is largely completed by the subsequent forward sliding and gentle agitation of the coal on the downward incline 25. It is to be noted that on the incline 24 the coal slides in a direction opposite to that of the conveyor-screen travel; while on incline 25 the coal slides in the same direction as the travel of the conveyor-screen. As already explained, by the time the coal has passed over the hump or knuckle the fines are substantially completely separated from the lumps, which latter are then carried along the second substantially horizontal run 26 of the screening and conveying surface. This section of the conveyor-screen forms a picking table, affording an opportunity for persons stationed on both sides of the apparatus to pick out lumps of slate and other incombustible matter mixed with the salable coal. From the picking table the good lump coal falls into a chute 28 and thence into a railroad car, bin, or the like. The separated fines are

collected and conveyed to a separate point of discharge as will be hereinafter described.

In the desirable practical construction here illustrated, the conveyor-screen 10 comprises a series of pans or aprons 29 connected together to form an endless screening and conveying surface 11 attached to and carried by two strands 12 and 13 of endless roller chain. Each strand of roller chain comprises two series of side bars or links 30 and 31. The links of each series are pivotally connected to one another by pins 32 which also form means for connecting each of the series of links in each strand and also for pivotally supporting rollers 33 which space the two series of links. The rollers 33 travel on track 34. The track 34, which has a substantially horizontal section, an upwardly-inclined section, a downwardly-inclined section, and a second substantially horizontal section, corresponding to the described conveyor sections, supports the conveyor-screen between the sprocket wheels 14, 20 and 15 respectively. It will be observed that the inside pieces or links 30 of each strand of roller chain also form the side pieces of the pans 29. The bottoms 35 of the pans 29 are secured to the side pieces 30, which also form one side of the roller chains, by angle brackets 36 riveted or otherwise connected to the sides and bottoms of the pans. It has previously been explained that when the conveyor-screen advances or travels up over the hump or "knuckle" and down again a certain amount of sliding of the coal being carried on the conveyor-screen will take place. I have provided a specially constructed pan bottom in order that free-running or uncontrolled sliding of coal on the inclines of the hump will be guarded against, but which will allow the regulated or retarded sliding of the coal so desirable to obtain complete screening and separation of fines from lumps. The bottom piece 35 of each pan 110 comprises a portion 37, forming the bottom of the pan, which has a downwardly depending end portion or flange 38 which is bent substantially at right angles to portion 37. The portions 37 of the pan bottoms 115 are provided with screening apertures or slots 39 which extend slightly past the bend into the bent portion or flange 38 as shown at 39a. The pan bottoms are so secured to the side pieces forming a part of the chains that when the strands of chain are in a horizontal position, the larger portion 37 will have a comparatively gradual upward incline or slope and the angular bent end portion 38 will have a short, steep downward incline, almost vertical. When a series of pans are connected together, assuming the strands of chain to be horizontal, a conveying and screening surface is formed composed of the successive gradually-in-

clined portions 37 connected by the successive steep, oppositely-inclined, almost vertical portions 38. The conveying and screening surface so formed is substantially 5 zig-zag in longitudinal contour. The gradually inclined portions 37 support and carry the material while the portions 38 form shoulders or abutments to prevent undue sliding of the material especially on the inclines of the hump and ensure it being carried along. It will be seen therefore that a screening and conveying surface is formed which will prevent free-running or uncontrolled sliding of coal on the inclines 10 of the hump, but permit regulated or retarded sliding of the coal. On the upward incline the shoulders 38 of the pans 29 support the coal and prevent free-running thereof, yet at the same time they permit 15 some of the coal to slide over the inclined screen bottoms 37. The screening perforations or slots 39 in the screening bottoms 37 extend over the bends and into a part of shoulders or abutments 38 so that as the 20 coal slides over the abutments the fines may more readily be separated. On the downward incline the portions 37 form a series of comparatively gradually sloped stepped inclines sloping downward in the same general 25 direction as the conveyor-screen, but more gently. This allows a further retarded sliding and screening of the coal.

I have provided means for receiving the fines separated from the lumps, together 30 with means for advancing the fines to a designated point of discharge. Fines sifting through the conveying and screening surface are caught in a trough 40 which is supported immediately under the whole 35 length of the coal-carrying part of the conveyor-screen. Means are provided for advancing the screened material or fines received by the conveyor-trough 40 and carrying such material to a point of discharge. 40

45 In this instance, pushers or scrapers 41 depending from the conveyor-screen into said trough serve this purpose. Any desired number of scrapers or pushers may be carried on the underside of the conveyor-screen at suitable distances apart. In the apparatus 50 illustrated, each pusher or scraper is an integral part of a pan 29. The bottom 35 of the pan 29 is, in reality, of inverted through-shape, made of a single piece of stamped metal, the portions 37 and 38 going to make up the conveying and screening surface; the depending portion 41 forming the scraper or pusher working in conveyor-trough 40. As has already been explained, 55 the conveyor-trough extends under the whole length of the coal carrying surface of the conveyor-screen and the sifted material is advanced along the conveyor-trough by the depending pushers or scrapers 41. 60

65 However, as the fines have been largely separated from the lumps at the junction of the downward incline 25 and the horizontal portion 26, an opening 42 is provided at this point in the bottom of the trough leading into a transverse screw conveyor 43 connecting with the chute 44 by which the fines may be conducted to a railway car, bin or otherwise disposed of. The opening 42 in the bottom of the conveyor-trough is provided with a sliding gate 45 operated by wheel 46 70 so that if desired only a part of the fines may be disposed of here or the gate may be entirely closed and all the fines carried onto the screw-conveyor 47 emptying into chute 48. 75

The operation of the apparatus is sufficiently clear from the foregoing description and will not therefore be repeated. It is sufficient to point out that as the run of the mine coal is received onto the conveyor-screen from chute 27, the coal will be partly screened in landing on the conveyor-screen and will be effectively screened after passage over the inclines of the hump or knuckle. The construction of the pans between the two strands of roller chain is such that they not only screen the coal, but carry the lumps on the top side and push the fine coal along in the trough below. It will be observed that at no time is the coal subjected to undesirable shaking or rough agitation, tending to break up the lumps and form additional quantities of fines; this being adequately prevented notwithstanding the fact that the fines are completely separated from the lumps by apparatus which takes up little, if any, more space than is required for the usual type of endless conveyor alone. 90

It is obvious that various changes can be made in the details of the apparatus without departing from the broad invention disclosed herein and set forth in the annexed claims. 100

What I claim is: 110

1. Conveying and screening apparatus comprising, means providing a traveling conveying and screening surface inclined upwardly and then downwardly between a point of feed and a point of discharge whereby material carried by said surface will be agitated and a conveyor-trough for screened material under said conveyor and screening surface and extending throughout the area of upward and downward inclination of said surface. 115

2. Conveying and screening apparatus comprising, means providing a traveling conveying and screening surface inclined upwardly and then downwardly to a degree greater than the angle of repose of the material upon a plane surface between a point of feed and a point of discharge, and having provision for retarding free-running of material on the inclines. 125 130

3. Conveying and screening apparatus comprising, in combination, means providing a traveling conveying and screening surface inclined upwardly and then downwardly between a point of feed and a point of discharge, provision being made to retard free-running of material on the inclines, a conveyor-trough supported under said conveying and screening surface, and means associated with said surface working in said conveyor-trough to advance screened material along said conveyor-trough.

4. Conveying and screening apparatus comprising, means providing a traveling conveying and screening surface inclined upwardly and then downwardly to a degree greater than the angle of repose of the material upon a plane surface between a point of feed and a point of discharge, said conveying and screening surface being provided with shoulders or abutments to retard free-running of material carried by said conveying and screening surface.

5. Conveying and screening apparatus comprising, means providing a traveling conveying and screening surface inclined upwardly and then downwardly between a point of feed and a point of discharge, said surface comprising a plurality of connected sections inclined with respect to the direction of travel of the conveying and screening surface, each of said sections being provided with an abutment or shoulder portion.

6. Conveying and screening apparatus comprising, in combination, means providing a traveling conveying and screening surface inclined upwardly and then downwardly between a point of feed and a point of discharge, said means comprising a plurality of connected sections each having a conveying and screening surface inclined with respect to the general direction of travel of the conveying and screening surface as a whole, each of said sections being provided with an abutment or shoulder portion, a conveyor-trough supported under said conveying and screening surface, and means traveling with said conveying and screening surface for advancing material along said conveyor-trough.

7. Conveying and screening apparatus comprising, a conveyor inclined upwardly and then downwardly between a point of feed and a point of discharge, said conveyor comprising an endless series of connected pans, each of said pans having an apertured bottom inclined with respect to the direction of travel of said conveyor and assuming differing positions with respect to the horizontal in the travel of said conveyor through its said upward and downward inclinations.

8. Conveying and screening apparatus comprising, a conveyor inclined upwardly and then downwardly between a point of feed

and a point of discharge, said conveyor comprising an endless series of connected pans, each of said pans having a bottom provided with screening apertures and inclined with respect to the direction of travel of said conveyor, said bottom having a depending abutment or shoulder portion extending toward the bottom of the next succeeding pan in the series.

9. Conveying and screening apparatus comprising, a conveyor inclined upwardly and then downwardly between a point of feed and a point of discharge, said conveyor comprising an endless series of connected pans, each pan having a screening bottom inclined with respect to the direction of travel of said conveyor, said bottom having a depending abutment or shoulder portion extending toward the bottom of the next pan in the series and an integral depending pusher or scraper, in combination with a conveyor-trough supported under said conveyor in which said pushers or scrapers are adapted to work.

10. Conveying and screening apparatus comprising a conveyor inclined upwardly and then downwardly between a point of feed and a point of discharge, said conveyor comprising an endless series of connected pans, each pan having a bottom inclined with respect to the direction of travel of said conveyor, said bottom having a depending abutment or shoulder portion adapted to extend toward the bottom of the next pan when the pans are connected, the bottom of each pan being provided with slots or apertures which extend into part of the depending abutment or shoulder portion, in combination with a conveyor-trough supported under said conveyor, and means carried by the conveyor for advancing material along said conveyor-trough.

11. Conveying and screening apparatus comprising an endless series of connected pans forming a conveyor, each of said pans having a bottom provided with screening apertures and inclined with respect to the direction of travel of said conveyor and assuming differing positions with respect to the horizontal in the travel of said conveyor through its said upward and downward inclinations.

12. Conveying and screening apparatus comprising an endless series of connected pans forming a conveyor, each of said pans having a screening bottom inclined with respect to the direction of travel of said conveyor, said bottom having a depending abutment or shoulder portion extending toward the bottom of the next pan in the series.

13. Conveying and screening apparatus comprising an endless series of connected pans forming a conveyor, each of said pans having an apertured bottom inclined with respect to the direction of travel of said

conveyor, in combination with a conveyor-trough supported under said conveyor and means carried by said conveyor for advancing material in said conveyor-trough in the 5 direction of travel of said conveyor.

14. Conveying and screening apparatus comprising an endless series of connected pans forming a conveyor, each of said pans having an apertured bottom inclined with 10 respect to the direction of travel of said conveyor, said bottom having a depending abutment or shoulder portion extending toward the bottom of the next pan in the series, in combination with a conveyor-trough and 15 means carried by said conveyor to advance material in said conveyor-trough.

15. Conveying and screening apparatus comprising an endless series of connected pans forming a conveyor, each of said pans 20 having a screening bottom inclined with respect to the direction of travel of said conveyor, said bottom having a depending abutment or shoulder portion extending toward the bottom of the next pan in the series and 25 an integral depending pusher or scraper, in combination with a conveyor-trough supported under said conveyor in which said pushers or scrapers are adapted to work.

16. Conveying and screening apparatus 30 comprising in combination, a conveyor embodying two endless strands of roller chain, a track on which said roller chains are adapted to travel, a series of pans connected

to and carried by said strands of roller chain, each of said pans provided with a 35 bottom having screening apertures and inclined with respect to the directions of travel of said conveyor, said conveyor inclined upwardly and then downwardly between a point of feed and a point of discharge, a conveyor-trough supported under 40 said conveyor and means carried by said conveyor for advancing material along said conveyor-trough.

17. In conveying and screening apparatus, a conveyor element comprising side pieces and an apertured bottom piece secured to said side pieces in an inclined position relative to said side pieces, said bottom piece having a depending portion adapted 45 to extend toward the bottom of the next succeeding element when the elements are connected in series.

18. In conveying and screening apparatus, a conveyor element comprising substantially 50 parallel side pieces and a bottom piece connected to said side pieces and inclined in relation thereto, said bottom piece having a depending pusher portion and a depending shoulder portion, the bottom piece having 55 screening apertures which extend into part of the shoulder portion.

In testimony whereof I hereunto affix my signature.

EUGENE E. LANDAHL.
